(57) **CLAIM**

The ornamental design for a pot assembly, as shown and described.

DESCRIPTION

FIG. 1 is a front perspective view of a component of a pot assembly showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view of another component of the pot assembly;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a front perspective view of the pot assembly showing the pot, the stove and a base of the pot assembly before assembling; and,

FIG. 16 is another front perspective view thereof showing the pot assembly after assembling.

The dash-dash broken lines in FIGS. 1-16 represent portions of the pot assembly. The dot-dash broken lines in FIGS. 1-6 and 15-16 represent boundary. The broken lines form no part of the claimed design.
